ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS.

WASHING MACHINE.

Application filed March 25, 1927. Serial No. 178,181.

This invention has reference to new and useful improvements in washing machines and it has for its principal object to improve the tub and agitator or dolly structure carried thereby; whereby, the washing fluid is so agitated that at suitable points in the tub the velocity of such fluid is increased, while at the same time the materials suspended in such fluid are retarded in their circumferential movement about the axis of the agitator and thereby a more effective circulation of the water through the materials brought about; the oscillation of the agitator and retardation of the materials causing the latter 10 to float or move upwardly and radially of said tub.

To facilitate in the carrying out of the above object I construct the wall of the tub with a plurality of obstructions, each at predetermined points and extending inwardly, and in the provision of an oscillatory agitator having circumferentially spaced wings, vanes or ribs disposed radially thereof; the 20 positioning of said obstructions in their relation to the oscillation of said wings, vanes or ribs on the agitator restricting the easy and normal circumferential movement of the materials to be washed, at these points, or in other words retarding their movement, but 25 accelerating the circulation of the water through such materials. Such materials therefore will float or move upwardly and due to the action of said wings, vanes or ribs will cause the same to move inwardly and 30 thence outwardly or in radial directions, quickly and effectively cleansing the materials.

The invention has for a further object to improve the bottom structure of the tub 40 and in the manner of mounting the agitator thereon to prevent materials moving thereunder during the agitation of the water and the cleansing of the materials; also in an improved manner of draining the tub.

That the invention may be more fully understood, reference is had to the accompanying drawings forming a part of the description, illustrating a preferred embodiment of the invention, in which:—

Fig. 1 is a top plan view of a washing tub embodying my invention, the agitator being omitted;

Fig. 2 is a side elevation partly in vertical section, including the agitator and as the same would appear on the line 2—2 Fig. 1; 55

Fig. 3 is an enlarged sectional detail of the coacting portions of the tub bottom and agitator which prevent materials moving under the agitator, and

Fig. 4 is a sectional detail in perspective 60 as the same would appear on the line 4—4 Fig. 1.

Like characters of reference denote corresponding parts throughout the figures.

The drawing shows in plan and in side elevation, partly in section, a washing tub for a washing machine constructed in accordance with my invention, and which I have elected to show such tub as approximately square in outline and of suitable depth, it is to be 65 understood that the vertical wall portion of said tub may present a circular appearance or other shape, as may be desired. Also, while I have elected to show said tub made preferably of sheet metal, it may be made 70 of whatever material is best suited for the purpose in a washing machine.

The outer vertical wall 1 of the tub stands perpendicular for the greater portion of its height and is curved inwardly and downwardly, as at 2, terminating in a bottom wall portion 3 formed or provided with the rather large axially disposed annular shaped opening 4. Next adjacent the wall or edge forming the opening 4, the bottom 3 lies substantially flat, providing in effect a flat ring like portion 5. This ring or flat portion terminates in the off-set or shouldered and upwardly and outwardly inclined portion 6, and from thence to the point where the bottom 3 and the vertical wall meet in the curved portion 2, said bottom 3 slopes upwardly and outwardly to provide, what may be described as the inclined shelf 7 of said bottom. At the juncture of said shelf portion 7 and the 80 curved portion 2, the bottom is formed or provided with an annular depending groove 8 or seat 8. Water within the tub circulates in the groove 8 and through radially arranged troughs 9, see Figs. 1 and 4 and over the ring like portion 5 and into the opening 4 in said bottom.

Underlying the bottom 1 and secured thereto and covering the opening 4 is a plate 10, with

a water seal 11 interposed between said plate and bottom, see Fig. 2. Such plate has a discharge outlet 12, see Fig. 1, which is adapted to communicate with and discharge into any 5 suitable valved connection or coupling, not shown. The upper edge of the wall 1 is provided with the strengthening rib or flange 13.

The plate 10 has an axial opening therethrough through which upstands a sleeve like 10 stem 14, flanged, as at 15 and between said flange and plate 10 a water seal is provided. The stem is secured in position by the nut 17 secured thereon and bears against the underside of the plate 10, see Fig. 2. Operating 15 within said stem and adapted for connection, in a manner not shown, with the upper end of a sleeve 18 of an agitator 19, is the shaft 20, which is operated from below the tub by a source of power, not shown.

20 The agitator 19 includes an annular plate like base formed or provided with a central vertical hub 21 connected in any suitable manner with its sleeve 18, the latter with said hub, and therefore the agitator revolving on the 25 flange 15 of said stem 14. Such an arrangement positions the underside of the agitator base above the plane of the tub bottom provided by the annular groove or seat 8 in said tub bottom and the outer or peripheral edge 30 of the agitator is formed or provided with a depending annular flange 22 adapted to be seated and revolved within the said groove or seat 8 and thereby, clothes and other materials being agitated within the tub cannot enter or 35 wedge between the bottom of the agitator and the bottom wall of the tub and the tearing or damaging of the materials obviated. The outer face of the flange 22 and the upper surface of the base of the agitator merge into 40 each other by an upwardly inclined surface 23, see the dotted lines in Fig. 3, which aids in the easy movement of materials over the base of the agitator during the radial and whirl-like circulation of the materials, as a result 45 of the agitation produced by the rotation of the agitator.

The agitator is provided with two or more 50 radial wings, vanes or ribs 24 which extend between the hub 21 thereof and its peripheral edge, with the outer wall portion of said wings, vanes or ribs rising preferably vertically for a predetermined distance, as at 25, then curved upwardly and inwardly, as at 26, and then sloping inwardly and downwardly, 55 as at 27 and thence upwardly and inwardly, as at 28 to unite with the hub 21. This formation of the wings, vanes or ribs, as the agitator is alternately rotated, will impart through the agitation of the water circumferential movement in opposite direction to the materials, with the materials moving or floating 60 inwardly and upwards and radially of the tub. The surface formation of the wall of the wings, vanes or ribs facilitating, rather than 65 retarding such movement. However, such

agitation of the materials is further accentuated by the peculiar construction given to the side wall 1 of the tub, as I shall explain.

The wall 1 of the tub at predetermined points is formed or provided with interiorly 70 disposed obstructions 29, preferably arcuate in shape and merging in an easy slope into the wall. So constructed, the path of circulation of the water therebetween and the agitator is somewhat restricted, so that the velocity of 75 the water at such points is somewhat accelerated or increased, while at the same time the movement of the materials is retarded in their circumferential movement about the axis of the agitator and thereby a more effective circulation of the water through the materials brought about; the oscillation of the agitator and retardation of the materials causing the latter to float or move upwardly and radially 80 of the tub. In the present instance the obstructions are preferably provided by forming concave depressions in the tub wall, the convex portions lying within the tub, see Fig. 1. Also I prefer that the wall of such concave depressions shall slope or incline upwardly 85 from their lower to their upper ends, see Fig. 2. Furthermore if the wall of the tub is rectangular in outline, with four sides, as shown in Fig. 1 a depression may be disposed mediate thereof, or if desired at a point to one side 90 of a line passing transversely through the tub, as shown at the right in Fig. 1. Such an arrangement will permit of the depression serving an additional purpose, such as a seat for a machine element, not shown, which it may 95 be desirable to position closer than heretofore to the axis of the tub. I have in mind the attachment of a centrifugal drier or extractor; also positioning such an element closer to one side of the machine than the other, which 100 makes for a more convenient handling of a washing operation. However, it is not to be inferred that the other depression may not be so used, as they may, even though located 105 more centrally.

110 What I claim is:—

1. A tub for a washing machine arranged for the support of an agitator therein and having its wall provided with a plurality of arcuately shaped obstructions lying within 115 the interior of the tub for the retardation of articles being washed, the wall forming such obstructions being inclined upwardly and inwardly throughout its length.

2. A tub for a washing machine having 120 a wall rectangular in outline, each side provided with interiorly extending projections arcuate in shape, and with one of such obstructions offset from a line passing transversely through the axis of the tub.

3. A tub for a washing machine having 125 a wall rectangular in outline, each side provided with interiorly extending projections arcuate in shape, having an inclined wall, and with one of such obstructions offset from 130

- 2 a line passing transversely through the axis of the tub.
4. A tub for a washing machine having its bottom wall provided with a shallow 5 annular water conducting groove and protecting guard for an agitator and with the bottom between such groove and its axial portion sloping downwardly and inwardly and provided with radially arranged water 10 conducting troughs in communication with said groove.
5. In combination, a tub having a bottom provided with a shallow annular water conducting groove and protecting guard for an 15 agitator and with radially arranged water conducting troughs in communication with said groove, and an agitator revolvably supported in said tub with its bottom normally positioned in a horizontal plane above said 20 groove and with a sloping and downwardly projecting annular flange at its periphery revolvble in said groove.
6. In a washing machine, a tub having a bottom and side walls merging thereinto in 25 a gradual curved portion, said bottom having an annular depressed portion forming a shallow water conducting groove at substantially the points of juncture of the curved portion, and an agitator having an annular 30 depending edge which is rotatably received in said groove and which edge projects below the upper face of the bottom on the exterior of the groove.
7. In a washing machine, a tub having a 35 bottom formed with an annular shallow depressed water conducting groove, and an agitator having an annular peripheral portion formed with a depending free edge which extends into the groove and below the adjacent portion of the upper face of the 40 bottom on the exterior of the groove.
8. In a washing machine, a tub having a bottom formed with an annular water conducting groove which extends below the adjacent upper face of the bottom on the side 45 of the bottom exterior of the groove, and an agitator having an annular peripheral portion formed with a depending free edge which extends into said groove, said tub having a side wall which gradually curves toward and merges into the outer side of the groove, said free edge of the agitator extending below the lowest point of said curve of the side wall.
9. In a device of the class described, comprising a tub having side walls and a substantially flat bottom portion, a circular depressed ring in said tub, a vertically disposed drive shaft, a water impeller comprising a disk member, said disk member being 55 disposed adjacent the bottom of the tub and having its periphery downturned in a manner to lie within the circular depressed ring in such manner that the edge of the disk is lowered to a point substantially adjacent the 60 bottom of the tub, water agitating means on said disk and a driving connection between said water impeller and said drive shaft.
- In witness whereof, I have hereunto affixed my hand this 14th day of March, 1927.
- ALPHEUS W. ALTORFER.
